(57) **CLAIM**

The ornamental design for a helmet sun visor, as shown and described.

DESCRIPTION

FIG. 1 is a perspective view of our helmet sun visor; FIG. 2 is a front plan view thereof; FIG. 3 is back plan view thereof; FIG. 4 is a right side plan view thereof; FIG. 5 is a left side plan view thereof; FIG. 6 is top plan view thereof; FIG. 7 is bottom plan view thereof; and, FIG. 8 is bottom plan view thereof in a flexed configuration. Broken lines in FIGS. 1-8 represent unclaimed features and/or environmental structures, and are for illustrative purposes only, forming no part of the claimed design.
